UNITED STATES PATENT OFFICE.

HENRY A. BERNSTEIN, OF NEW YORK, N. Y.

ARCH AND ANKLE SUPPORT.

Application filed November 18, 1920. Serial No. 424,930.

To all whom it may concern:

Be it known that I, HENRY A. BERNSTEIN, a citizen of the United States, and a resident of the city of New York, borough of 5 Manhattan, in the county and State of New York, have invented a new and Improved Arch and Ankle Support, of which the following is a full, clear, and exact description:

The invention relates to arch and ankle supports such as shown and described in the Letters Patent of the United States, No. 1,211,955, granted to me on January 2, 1917.

The object of the present invention is to provide a new and improved arch and ankle support arranged to snugly fit the foot of the wearer with a view to firmly hold up the arch and to sustain the ankle without discomfort to the wearer or impeding the use of stockings and shoes.

Another object is to permit of readily placing the support in position on the foot.

With these and other objects in view, the invention consists of certain novel features of construction, as hereinafter shown and described and then specifically pointed out in the claim.

A practical embodiment of the invention is represented in the accompanying drawings forming a part of this specification, in which similar characters of reference indicate corresponding parts in all the views.

Figure 1 is a perspective view of the improved arch and ankle support as applied;

Figure 2 is an enlarged perspective view of the improved arch and ankle support; and

Figure 3 is a sectional side elevation of the bottom portion of the improved arch and ankle support in position on the wearer's foot.

The arch and ankle support in its general construction consists of an endless elastic band 10 twisted to form an arch loop 11 and an ankle loop 12, of which the arch loop 11 extends under the arch of the foot and over the instep. The ankle loop 12 passes around the ankle directly above the heel of the foot, as plainly indicated in Figure 1. In forming the loops 11 and 12, the portions 15 and 16 intermediate thereof cross each other at the top of the instep, and the intermediate portion 15 is provided with a slit 17 extending lengthwise of the band and through which the other intermediate portion 16 passes so that the two intermediate portions 15 and 16 are in sliding engagement one with the other.

In manufacturing the arch and ankle support a piece of an elastic band is used and a slit 17 is formed therein. The ends of the band are cut to form concave edges fastened together in abutting relation by stitches to provide an arched longitudinally extending seam 20 fitting the under side of the arch of the foot, as plainly shown in Figure 3. The loops 11 and 12 of the arch and ankle support are considerably smaller in size than the corresponding portions of the foot and hence when the support is drawn into position on the user's foot the elastic band expands and the loops 11 and 12 tightly engage the portions of the foot owing to the inherent resiliency of the elastic band. In placing the arch and ankle support in position on the foot it is only necessary for the user to pass the foot through the loops 12 and 11 and draw the loop 12 up on the ankle at the time the loop 11 is in position on the arch and instep of the foot.

It will be noticed that by providing the arched seam 20 the under side or bottom of the loop 11 fits snugly on the under side of the arch of the wearer's foot, as plainly shown in Figure 3, and hence an even pressure is exerted on the arch and instep by the action of the loop 11.

It will also be noticed that by passing the intermediate portion 16 through the slit 17 of the other intermediate portion 15 the portions are held in proper relation one to the other, at the same time allowing the intermediate portions to slide one on the other, and thus the foot is not liable to be cramped.

Having thus described my invention, I claim as new and desire to secure by Letters Patent:

As an article of manufacture, an arch and ankle support, comprising a comparatively wide elastic band of approximately uniform width throughout and having concave ends fastened together by stitches to form a lengthwise extending arched seam adapted to fit the under side of the arch of the foot, the said band being twisted to form an arch loop and an ankle loop, the loops standing approximately at a right angle one to the other, one of the portions of the band intermediate the loops having a slit through which extends the other intermediate portion of the band.

HENRY A. BERNSTEIN.
